F. N. CONANT

RENEWABLE ELECTRIC FUSE

Original Filed June 14, 1921

Inventor,

Franklin N. Conant

By
F. Greenwood Atty.

UNITED STATES PATENT OFFICE.

FRANKLIN N. CONANT, OF NEWBURYPORT, MASSACHUSETTS.

RENEWABLE ELECTRIC FUSE.

Refiled for abandoned application Serial No. 477,384, filed June 14, 1921. This application filed March 5, 1923. Serial No. 623,029.

To all whom it may concern:

Be it known that I, FRANKLIN N. CONANT, a citizen of the United States, residing in Newburyport, in the county of Essex and

5 State of Massachusetts, have invented an Improvement in Renewable Electric Fuses, of which the following is a specification.

This invention relates to a renewable enclosed electric fuse of the cartridge type

10 having knife blade fuse terminals. In certain respects it is an improvement upon the Gibbs Patent No. 797,054, and my Patent No. 1,422,419, dated July 11, 1922. In such fuses effective means should be provided to

15 prevent the highly heated gases which are formed when the fusible element is blown on short circuit from being expelled in a direct line outwardly along the blades. This result can be accomplished by the use

20 of a finely divided filling material or perishable washers, and in other ways with more or less success. It is my object to accomplish this result by a structure containing a small number of large parts; durable and

25 easily assembled without the aid of tools, which I believe to be better than any hitherto used. It is also my object to provide an apparatus which will continue to be effective notwithstanding the usual inaccuracies in

30 commercial manufacture, and the changes due to repeated blowings of the fuse.

It is also my object to combine the end closing means with means for preventing rotation of the blades and an adjustable gas

35 check in a single element.

A further object is generally to improve the construction and operation of electric fuses.

Fig. 1 is a plan view, partly broken away, 40 of an enclosed electric fuse having knife blade fuse terminals and embodying my invention.

Fig. 2 is a sectional detail along line 2—2 of Fig. 1.

45 Fig. 3 is an end view of Fig. 2.

Fig. 4 is an end view of Fig. 2 with the end cap removed.

Fig. 5 is an end view of Fig. 2 with the end cap and gas sealing means removed.

50 Fig. 6 is a transverse sectional view through the gas sealing means.

Fig. 7 is a view of the inner end of the gas-sealing means disposed on a knife-blade terminal.

Fig. 8 is a view of the gas sealing means 55 of Fig. 2, with the knife-blade locking disc removed and exposing to view the gas-sealing members.

Fig. 9 is a view similar to Fig. 7 with the gas sealing members in clamping position 60 on the knife blade.

Fig. 10 is a plan view of the gas-sealing members.

Fig. 11 is an end view of Fig. 10.

As here shown the fuse embodying my 65 invention includes the insulating tubular enclosing casing 10. A ferrule 11 is fixed securely on the end thereof by pins 12 in the usual manner, or by other suitable means. Said ferrule is composed of metal and has 70 the externally screw-threaded portion 13 adapted to receive removably an interiorly-threaded end cap 14. Said ferrule is formed with an inturned lip or end-wall 15 which extends over the end of the casing; 75 and said end-wall is formed with the aperture 16 and a pair of notches 17 extending outwardly from said aperture at diametrically opposite points. Said end wall is or may be also formed with the vent passages 80 18 therein through which gas is or may be discharged from the interior of the casing 10 into the space between the ferrule and end cap after a long passage between cool metal surfaces; and gas may also escape 85 from the interior of said casing through the aperture 16 and notches 17.

The knife-blade fuse terminal 19, which is made as a blade or flat plate, has suitable means for the renewable attachment of the 90 fusible element, for instance, a bolt-receiving aperture in its inner end adapted to receive the bolt 20 by which the fuse link 21 is secured to said terminal; and said terminal also has the oppositely disposed notches 95 22, 22 in its edges which receive the end-wall 15 when said blade is projected through the aperture 16 in the end wall of said ferrule by way of the notches 17 therein and turned a quarter of a revolution. 100 With this construction the terminal is held in the casing against longitudinal movement.

The end closure consists of the cup 23 having the flat end wall 24 and the outwardly flaring side wall 25 the inner face 25^a of which is adapted to form an annular cam face as will hereinafter be described.

The end wall of said cup is formed with an elongated slot 26 adapted removably to receive the knife-blade fuse terminal. Two semi-circular wedging plates or gas sealing members 27 are received within said cup and comprise plates formed preferably with bevelled peripheral edges 27^a adapted to conform with the slope of and engage the inner cam face 25^a of said cup. Said members 27 are formed with complementary recesses 28 therein arranged to receive the fuse terminal and be pressed in firm engagement therewith; and the faces 29 of said members are arranged to conform to the profile of and snugly engage said terminal and form a nearly gas tight seal between the members and said terminal. Said members are formed with elongated apertures 30 adapted to receive rivets by which the elements of the gas-sealing means are retained in operative relation to each other.

A pressure disc or plate 31 is disposed over said sealing-members. Said disc is formed with the struck-out, diametrically opposed lips 32 which are adapted to enter the notches 17 in the end ferrule 11 and lock the knife blade fuse terminal against rotary movement. Said disc is also formed with the aperture 33 adapted to receive the fuse terminal and inwardly extended lips 34, 34 on opposite sides of said aperture arranged to engage and provide increased bearing surface for the support of the terminal. Rivets 35 are loosely passed through apertures in said disc and the apertures 30 in said gas sealing members and are fixed in the end wall of said cup 23 thus making a single element of the end closing means, and the arrangement of the cup, sealing members and disc is such that all are loosely retained in position.

In assembling the fuse structure, the end closing element, the assembly of which is illustrated in Fig. 6, is slipped over the fuse terminal when the latter is in position in the casing, and disposed against the end wall of the ferrule 11 with the lips 32 in the notches 17. The end cap 14 is then screwed on the ferrule and forced against the end wall of the cup 23. If the end cap cannot be screwed into place readily by reason of the fact that the gas sealing members 27 do not slip together against the blades easily, the members 27 may be shaken into place if the tube is held with its axis vertical, but in general there is no difficulty in screwing on the end cap and forcing the gas sealing members 27 tightly against the terminal blades. The gas sealing members are thereby compressed between the pressure disc 31 and the cup and, by reason of the cam face 25^a of the cup will be forced inwardly toward each other and the edges 29 thereof will be brought into gas tight contact with the flat faces of the fuse terminal so that an

expulsion of gas from the interior of the casing over the surface of the fuse terminal will be prevented. The curved portions 29^a of the terminal-engaging face of said members are adapted to be in snug and substantially gas tight engagement with the edges of the fuse terminal and the members are arranged to be substantially in contact beyond the fuse terminal whereby there will be no substantially expulsion of gas at these points. 70

It will be noted that the gas-sealing means above described also acts as a terminal clutching means by which the terminal is held firm in the casing. 30

The end cap 14 is provided with a plurality of apertures 36 in its side wall and said apertures which form vent passages through which gas is expelled from the interior of the fuse casing. The outer diameter of the ferrule 11, beyond the threaded portion, is necessarily somewhat less than the internal diameter of the end cap so that an annular chamber 36^a is formed between the ferrule and end cap in which the gas will expand and be cooled before it is expelled through the vent apertures; and said apertures are preferably so disposed in the end cap that, when the cap is screwed in place, they communicate with the extreme inner end of said chamber, whereby to provide a long gas path over the cooling surfaces of the ferrule and end cap. This comparatively free release of the gas through the vents 36 cooperates with the gas seals 27 in preventing the hot gas from taking the short cut along the terminals. 95

The end closing element above described may also be applied as an attachment to many existing fuses of the general character above set forth. 105

It is obvious that the invention may be incorporated in modified structures without departing from the spirit thereof. 110

I claim:

1. A renewable enclosed electric fuse of the cartridge type comprising the combination of a tubular enclosing casing, a knife-blade fuse terminal extended outwardly from within the casing, plates having complementary terminal recesses therein adapted to conform to and envelop said terminal, and means arranged to press said plates inwardly toward each other and into substantial gas tight engagement with said terminal. 115

2. A renewable enclosed electric fuse of the cartridge type comprising the combination of a tubular enclosing casing, a knife-blade fuse terminal extended outwardly from within the casing, and wedging members having complementary terminal recesses therein adapted to conform to and envelop said terminal, said wedging members also having wedging faces, and means arranged 120

to engage said wedging faces and press said wedging members into gas tight engagement with said terminal and including an end cap carried by said casing and enclosing said 5 wedging members.

3. A renewable enclosed electric fuse of the cartridge type comprising the combination of a tubular enclosing casing, a knife-blade fuse terminal extended outwardly 10 from within the casing, an end cap removably threaded on the end of said casing, and means to seal the casing against expulsion of gas around said terminal including a plurality of complementary wedging members 15 having wedging faces arranged to be forced into engagement by said end cap, whereby said wedging members are forced into substantial gas tight engagement with said terminal.

29. 4. A renewable enclosed electric fuse of the cartridge type comprising the combination of a tubular enclosing casing, a knife-blade fuse terminal extended outwardly 25 from within the casing, an end cap removably threaded on the end of said casing, and means to seal the casing against expulsion of gas around said terminal including a plurality of complementary wedging members having faces shaped to conform to the profile of said terminal, and means to force said wedging members into gas tight engagement with said terminal including wedging means 30 associated with said end cap.

5. A renewable enclosed electric fuse of 35 the cartridge type comprising the combination of a tubular enclosing casing, a knife-blade fuse terminal extended outwardly from within the casing, means to seal the casing against expulsion of gas around said 40 terminal including a plurality of complementary wedging members having faces shaped to conform to the profile of said terminal and also having wedging faces, means to engage said wedging faces and force said 45 wedging members into substantial gas tight engagement with said terminal and an end cap removably screw-threaded on the end of said casing arranged to act on the aforesaid forcing-means.

50. 6. A renewable enclosed electric fuse of the cartridge type comprising the combination of a tubular enclosing casing, a knife-blade fuse terminal extended outwardly 55 from within the casing, and means to seal the casing against expulsion of gas around said terminal including a plurality of complementary wedging members having faces shaped to conform to the profile of said terminal, a cup having a cam face in which 60 said wedging members are received and arranged to force said wedging members into gas tight engagement with said terminal, and an end cap enclosing said wedging members and cup and removably threaded 65 on the end of said casing.

7. A renewable enclosed electric fuse of the cartridge type comprising the combination of a tubular enclosing casing, a knife-blade fuse terminal extended outwardly 70 from within the casing, and means to seal the casing against expulsion of gas around said terminal including a pressure plate disposed on said terminal, a plurality of complementary wedging members disposed on said terminal in front of said plate, 75 said wedging members having faces shaped to conform to the profile of said terminal, a cup having a cam-face adapted to bear against said wedging members and force them into gas tight engagement with said terminal, and an end cap enclosing said 80 wedging members and cup and removably threaded on the end of said casing.

8. A renewable enclosed electric fuse of 85 the cartridge type comprising the combination of a tubular enclosing casing, a knife-blade fuse terminal extended outwardly from within the casing, and means to seal the casing against expulsion of gas around 90 said terminal including a pressure plate disposed on said terminal, a plurality of complementary wedging members disposed on said terminal in front of said plate, 95 said wedging members having faces shaped to conform to the profile of said terminal, a cup having a cam-face adapted to bear against said wedging members and force them into gas tight engagement with said terminal, and an end cap enclosing said 100 wedging members and cup and removably threaded on the end of said casing, said end cap having vent apertures in it.

9. A renewable enclosed electric fuse of 105 the cartridge type comprising the combination of a tubular enclosing casing, an exteriorly threaded ferrule secured on the end of said casing, said ferrule having an end wall with an aperture and a pair of opposed notches therein, a knife blade fuse terminal having a pair of notches in which the end 110 wall of said ferrule is received, a pressure plate received on said terminal having a pair of lips entered in the notches in said end wall, a pair of complementary wedging plates disposed on said terminal having 115 faces shaped to conform to the profile of said terminal, a cup having a cam face arranged to engage and force said wedging plates into gas tight engagement with said terminal, and an end cap removably screw-threaded on said ferrule arranged to compress said cup, wedging plates and pressure plate between it and the end wall of said ferrule.

10. A renewable enclosed electric fuse of 120 the cartridge type comprising the combination of a tubular enclosing casing, an exteriorly-threaded ferrule secured on the end of said casing, said ferrule having an end wall with an aperture and a pair of op- 125

posed notches therein, a knife blade fuse terminal having a pair of notches in which the end wall of said ferrule is received, a pressure plate received on said terminal having a pair of lips entered in the notches in said end wall, a pair of complementary wedging plates disposed on said terminal having faces shaped to conform to the profile of said terminal, a cup having a cam 10 face arranged to engage and force said wedging plates into gas tight engagement with said terminal, rivets loosely connecting said cup and wedging plates and pressure plate, and an end cap removably screw-threaded on said ferrule arranged to compress said cup and wedging plates and pressure plate between it and the end wall of said ferrule.

11. An attachment for a renewable enclosed electric fuse of the cartridge type having a knife-blade fuse terminal, which comprises a cup having a terminal receiving slot and an annular cam face, a pair of wedging plates received in said cup arranged peripherally to engage the annular cam face of said cup, said plates having complementary recesses therein arranged substantially to conform to the profile of said terminal, a pressure plate disposed upon said wedging plates and having a terminal receiving slot, and means to secure the above named elements loosely together.

12. An attachment for a renewable enclosed electric fuse of the cartridge type having a knife-blade fuse terminal, which comprises a cup having a terminal-receiving slot and an annular cam face, a pair of wedging plates received in said cup arranged peripherally to engage the annular cam face of said cup, said plates having complementary recesses therein arranged substantially to conform to the profile of said terminal, a pressure plate disposed upon said wedging plates and having a ter-

minal receiving slot, and rivets loosely connecting the aforesaid elements. 45

13. An attachment for a renewable enclosed electric fuse of the cartridge type having a knife-blade fuse terminal, which comprises a cup having a terminal-receiving slot and an annular cam face, a pair of wedging plates received in said cup arranged peripherally to engage the annular cam face of said cup, said plates having complementary recesses therein arranged substantially to conform to the profile of said terminal, a pressure plate disposed upon said wedging plates having a pair of oppositely-disposed lips and a terminal receiving slot and a pair of lips arranged to engage the terminal, and rivets loosely connecting the aforesaid elements.

14. In an enclosed electric fuse of the cartridge type, the combination of a ferrule 65 ruled insulating fuse casing having an in-turned lip at the end of the ferrule with oppositely-disposed notches, and a fusible element having a terminal blade with notches in its edges for engaging said lip by way of the notches therein, a pressure 70 plate for the terminal blade which substantially closes the open end of the casing, and lips fitting with the notches in the inturned lip of the ferrule and other lips hugging the terminal blade, a pair of wedging plates 75 having complementary recesses therein arranged substantially to conform to the profile of said terminal, a cup having a terminal receiving slot and an annular cam face arranged to engage the periphery of said 80 wedging plates and press them into engagement with said terminal, and an end cap exerting pressure on said cup and wedging plates and pressure plate and holding the parts assembled. 85

In testimony whereof, I have signed my name to this specification.

FRANKLIN N. CONANT.
